UNITED STATES PATENT OFFICE.

WILLIAM M. SMITH, OF WEST MERIDEN, CONNECTICUT, ASSIGNOR TO THE MERIDEN BRITANNIA COMPANY, OF SAME PLACE.

DESIGN FOR COFFIN-PLATE.

Specification forming part of Design No. 7,857, dated April 7, 1874; application filed March 26, 1874.
[Term of Patent 14 years]

A.

To all whom it may concern:

Be it known that I, WILLIAM M. SMITH, of West Meriden, in the county of New Haven and State of Connecticut, have invented a new Design for Coffin-Plate; and I do hereby declare the following, when taken in connection with the accompanying drawing and the letters of reference marked thereon, to be a full, clear, and exact description of the same, and which said drawing constitutes part of this specification, and represents a front or top view.

This invention relates to a design for the name-plate used upon coffins; and consists in a plate in the form of a partially-unrolled scroll with a roll at one or both ends, as shown in the accompanying illustration.

A B represent two rolls, one at each end of a scroll, C.

Either of the rolls may be dispensed with, one only being essential to complete the design; and I therefore do not wish to be understood as confining myself to the presence of two rolls.

I claim as my invention—

The design for coffin-plate, as shown and herein described, consisting of a representation of a scroll with a roll at one or both ends.

WILLIAM M. SMITH.
